(57) **CLAIM**

The ornamental design for a waste collector, as shown and described.

DESCRIPTION

FIG. 1 is a front view of a waste collector in accordance with the present design, but shown disassembled for completeness of illustration;

FIG. 2 is a rear view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof, but shown assembled for completeness of illustration;

FIG. 8 is a front view thereof;

FIG. 9 is a rear view thereof;

FIG. 10 is a left-side view thereof;

FIG. 11 is a right-side view thereof;

FIG. 12 is a top plan view thereof; and,

FIG. 13 is a bottom plan view thereof.

The broken lines depict environmental structure that forms no part of the claimed design.

1 Claim, 11 Drawing Sheets
